UNITED STATES PATENT OFFICE.

HANS CHRISTAIN MILLER, OF GENOA, NEBRASKA.

CRANK-CASE BREATHER FOR INTERNAL-COMBUSTION ENGINES.

1,367,164.

Specification of Letters Patent.

Patented Feb. 1, 1921.

Application filed August 9, 1919. Serial No. 316,280.

To all whom it may concern:

Be it known that I, HANS CHRISTAIN MILLER, a citizen of the United States, and a resident of Genoa, in the county of Nance and State of Nebraska, have invented certain new and useful Improvements in Crank - Case Breathers for Internal - Combustion Engines, of which the following is a specification.

10 My invention relates to improvements in internal combustion engines, and has reference more particularly to crank case breathers for such engines.

In internal combustion engines of the 15 closed crank case type, as commonly used on cars, trucks, and tractors, there is a continual alternating pressure and vacuum created in the crank case during operation of the engine caused by the reciprocating parts 20 contained in the crank case. This pressure and vacuum is relieved ordinarily by an opening in the crank case, the opening being covered by a removable cap called the "breather cap." As these engines are very 25 often operated in very dusty atmospheres, especially those used in tractors, and because of the surging in and out of the crank case air, a large amount of dust and grit is drawn into the case with the air. This dust 30 and grit of course proves very detrimental to the moving parts contained in the crank case.

An object of my invention is to overcome 35 these defects and to prevent the entry of dust and grit into the crank case.

Another object is to provide means for 40 supplying the crank case with lubricating oil required by the engine and by the same prevent the entry of dust and grit into the crank case and to retain entering dust and grit against entrance to the crank case and provide means whereby the same may be 45 readily cleaned out or removed as occasion requires.

Another object is to provide breather 50 means that will prevent undue compression within the crank case and at the same time prevent entry of dust and other foreign substances into the crank case.

With these and other objects in view 55 which will more clearly appear as the description proceeds, my invention consists in certain novel features of construction and arrangement and combination of parts, as

will be hereinafter fully described and 55 pointed out in the claims, reference being had to the accompanying drawing, in which:

Figure 1 is a sectional elevation of a portion of an engine crank case and my improvements applied thereto, said improvements being shown in vertical section,

Fig. 2 is a plan view looking into the expansion chamber with the cover removed,

Fig. 3 is an inside plan view of the cover removed.

The main body of the crank case which is conventional and needs no detailed description is designated as A and carries therein the usual crank shaft crank pin and pitman designated generally by B.

Adjacent the upper part of the crank case, the breather tube C is applied to the opening D in the wall of the crank case. The breather tube is a curved or bent elbow and has fitted to its upper end the cap which 75 comprises a cylindrical casing E having a circular central opening F in its bottom wall, extending upwardly from which is a circular drum G, said drum extending upwardly to within a short distance of the lid 80 or cover H of the casing. The casing is supported on the breather tube by means of a tubular extension or collar I which fits on the upper open end of tube C being rigidly held against an annular shoulder or rib c. 85

Extending upwardly from the bottom of the casing between the drum G and its outer wall is another drum J concentric with the drum G and of the same height. Through the bottom of the casing is a circular series 90 of openings K leading from the atmosphere to the annular space between the outer wall of the casing and the drum J.

The top of the casing is closed by a cover H which has a flange or rim h which fits 95 tightly the outside wall of the casing and this cover has projecting downwardly therefrom annular drum L between the central drum G and the intermediate drum J of the casing, and concentric therewith, the lower 100 end of said drum which projects inwardly from the cover, not extending however entirely to the bottom of the casing but terminating a short distance thereabove.

The cover H is removable because the 105 breather opening D is generally used as a means through which to pour lubricating oil required by the engine, so that by re-

moving the cover this lubricating oil can be readily poured into the opening D.

As the drums G and J carried in the main body of the casing are shorter than casing, 5 and the drum L carried by the cover is also shorter than the casing, and as these drums are concentrically arranged, there will be lateral spaces S left inside the casing, both at the top and bottom thereof, and that a 10 tortuous passage is provided for the air which enters through the circular series of small openings in the bottom of the casing, as indicated by the arrows in Fig. 1.

As this construction and relative arrangement of parts provides a chamber for the 15 expansion of the surging air from the crank case, the velocity of the incoming air is materially reduced, and this, with the tortuous passage created prevents the entry of dust, 20 etc., into the crank case. This is so because the outgoing air only reaches a point above one half way through the air passages, and this also applies to the incoming air.

Furthermore, as the outgoing air from a 25 crank case always carries an oil mist with it, this mist is condensed on the walls of the air passages and the incoming air being directed against these oil coated walls, the dust carried by it is caught by the oil 30 and retained there until the breather cap or casing is cleaned.

The expansion chambers of course, are to 35 be properly proportioned to the size of the engine upon which it is used.

While I have shown my invention applied 40 to engines in which the breather tube is connected at one end to the crank case and having the breather cap attached at its other end, it is obvious that it may be used with 45 engines in which the breather opening is an extension cast integral with the crank case. Furthermore, it can be used on other engines where the breather opening is located on the timing gear case, the breather air in this type of engine going through the time gear case to reach the crank case; this 50 is notably so of the Ford car.

I claim:—

1. A breather for engine crank cases, comprising in combination a breather tube opening laterally at its lower end into said crank case and its upper portion extending vertically therefrom, a removable cylindrical expansion chamber carried at the upper end of said tube, said chamber having an imperforate top wall, and a relatively large central circular opening in its bottom wall, a circular open-ended drum extending upwardly from said central opening and terminating free from the said upper imperforate wall, a plurality of partitions extending alternately in opposite directions from the upper and lower walls, concentric with the said central drum and between the same and the outer wall of the expansion chamber, the aforesaid lower wall having a circular series of perforations therethrough between the outer wall of the cylinder and its proximate partition. 55

2. In an engine of the character specified, 60 the combination of a crank case adapted to contain lubricant, a working cylinder, a breather tube opening laterally into the crank case and extending upwardly therefrom at one side thereof, a cylindrical expansion and separating chamber having a flat imperforate upper wall, said chamber mounted on the upper end of said breather tube and extending laterally beyond the periphery of the tube, a plurality of concentric partitions within the aforesaid chamber extending alternately in opposite directions from the top and bottom walls of the chamber, said partitions with the outer wall of the chamber forming concentric annular 65 communicating spaces, the bottom wall of the chamber having a central opening communicating with the upper end of the breather tube, and provided with series of relatively small perforations extending 70 therethrough into the outermost annular space. 75

HANS CHRISTAIN MILLER.
